HYDRAULICALLY OPERATED MACHINE
TOOLLouis G. L. Thomas, Glendale, Ohio, assignor to
Liberty Planers, Hamilton, Ohio, a partnership

Application November 3, 1943, Serial No. 508,829

3 Claims. (CL. 60—52)

1

This invention relates to machine tools in which a table is reciprocated over a bed through cutting and reverse strokes by means of a hydraulic actuating mechanism. The invention is disclosed in the environment of planing machines in which the table is moved along the bed in opposite directions through one or more hydraulic rams.

The principal objective has been to provide a hydraulic table actuating system which is simple and convenient to construct, less expensive and cumbersome than the units heretofore employed, and particularly free from chatter when the machine is being operated under load conditions.

A further objective of the invention has been to provide a hydraulic mechanism in which a plurality of cutting speeds may be obtained in conjunction with a plurality of rapid traverse feeds through which the table may be returned after a cutting stroke has been completed.

In a machine like a planer, where the length of table movement is substantial, it is desirable to provide a mechanism in which the rate of travel at which the table is returned is substantially greater than the speed during cutting. There is, consequently, a substantial difference in the volume of fluid required during the cutting stroke and during return traverse. On the other hand, the pressure of the fluid during cutting must be many times greater than the pressure required to return the table under no load conditions.

This invention, briefly, is predicated upon the concept of employing a relatively small positive pressure pump to furnish the limited volume of hydraulic fluid at the high pressure which is required during cutting, and to employ a centrifugal pump for furnishing the large volume of fluid at low pressure to provide for rapid table traverse. In this manner the size of the more expensive positive acting type of pump required for high pressure operation is kept at a minimum while the large volumes of fluid at low pressure which are necessary during the return stroke are furnished through an inexpensive centrifugal pump unit.

In preferred embodiments of the invention, though not necessarily, the positive displacement pump operates either directly against the pressure of the centrifugal pump discharge during the cutting stroke or against back pressure furnished through a metering circuit whereby, in either event, a predetermined loading of the table is obtained to prevent any chattering or undulating movements which otherwise might take place, especially if the cut is discontinuous. In

5 the former instance, hydraulic fluid previously introduced into the hydraulic ram during a return stroke is discharged through the centrifugal pump in a direction of flow which is opposite the normal centrifugal pump discharge. At the end of the cutting stroke infeed from the positive displacement pump is diverted from the actuating cylinder whereupon the pressure of the fluid discharged from the centrifugal pump immediately causes the table to move in an opposite direction.

10 Speed of return traverse is controlled conveniently either by throttling the centrifugal pump discharge, or by diverting a portion of the discharge through a bypass in such manner that continuous circulation is provided to prevent overheating of the fluid. In place of having the discharge from the positive displacement pump and the centrifugal pump act upon opposite ends of a piston in a single hydraulic cylinder two cylinders operate in opposite directions may be employed respectively to receive the high and low pressure pump discharges. Control or pilot valves are provided for shiftable diversion of the fluid flow at the end of the cutting and return strokes and such valves may be operated automatically through adjustable dogs provided at the table.

15 From these principles upon which the present invention is based and from the following detailed description of the preferred embodiment of the structure shown in the drawings, those skilled in the art readily will comprehend the modifications to which the invention is susceptible.

In the drawings:

20 Figure 1 is a plan view of a planer bed and table showing the pump and ram arrangement. In this figure and in the other illustrations of the drawings, the rail and its tool carrying saddle and feeding mechanism are omitted; they may be of the usual double housing, convertible, or open side type.

25 Figure 2 is a side elevation of a planer bed and table therefor equipped in accordance with the present invention.

30 Figure 3 is an end elevation of the bed and table showing portions of the hydraulic circuit.

35 Figure 4 is a representative hydraulic circuit in which centrifugal and positive displacement pumps cooperate with one another in accordance with this improvement.

40 Figure 5 is a diagrammatic view of an alternative type of circuit wherein a pair of hydraulic rams operating in opposite directions are employed to actuate the table through its cutting and reverse strokes.

2

The invention may be understood most conveniently by reference to Figure 4 in which the various elements shown diagrammatically are illustrated structurally in the other figures.

High pressure circuit

A positive displacement pump is indicated generally at 1, in Figure 4. It may be a pump of the constant volume or variable displacement type suitably driven by a motor to develop pressure sufficiently high to drive the table and the work mounted thereon past the tool during cutting operations. The pump 1 has its intake line 2 connected with a sump 3 located between the side walls of the bed or at the side thereof. In 10 the latter arrangement the positive pressure pump and driving motor are mounted directly over the sump for accessibility.

The pump 1 discharges through a line 4 to a pressure relief valve 5 which has a vent line 6 leading from it to the sump 3 for return of the relieved fluid. Thus, if the table for any reason becomes blocked against movement the relief valve actuates to prevent damage to the apparatus. Beyond the relief valve the high pressure pump discharge passes through a line 7, to a three-way valve indicated generally at 8, then on through a line 9 to the hydraulic ram 10, the line 9 containing a throttling valve 11 for controlling cutting speed. Ram 10 comprises a casing having a piston carried by a cylinder rod, these members being relatively interconnected between the table and the bed to effect movement of the table in one direction on the bed when fluid under high pressure is introduced into the cylinder at one side of the piston.

One suitable type of valve 8, as shown in the drawings, comprises a chamber 12 having a plunger 13 slidably arranged within it. The plunger has two annular grooves 14 and 15 delineating between them a blocking portion 16. The stem of the plunger which extends beyond the chamber at one end thereof is arranged to be moved either manually or by means of dogs mounted on the planer table, whereby the valve may control the cutting cycle. Vent lines 17 and 18 enter the valve chamber 12 at the opposite sides of the pump discharge line 7 and these, in turn, are interconnected with one another through a conduit 19 passing to the sump 3. The valve, in Figure 4, is shown in the position which it occupies when the table has just completed a return stroke and just before it is set to effect movement of the table in a "cut" direction. In this position discharge from the pump 1 passes through the line 7, through the annulus 15 in the valve plunger, and out through the lines 17 and 19 to the sump 3.

To effect a cutting stroke the valve plunger is lifted causing the portion 16 of the piston to be moved to the opposite side of the inlet port, thereby isolating the vent line 17; the lower portion of the plunger, at the same time, moves over the port connected with the return line 18. Thus, fluid under pressure is directed from the line 7, through the annular recess 14 and into the hydraulic ram 10 through the conduit 9. The throttling valve 11 enables the operator to vary the cutting speed at will by controlling the volume of high pressure fluid which is introduced into the ram.

Low pressure circuit

In the circuit shown in Figure 4, the pump arranged to deliver substantial volumes of fluid at

low pressure for rapid return traverse of the table is indicated generally at 21. This pump is of the centrifugal type and may be driven suitably by means of an independent motor 22 or the pump 21 may be driven in unison with pump 1 by motor 23.

Hydraulic fluid is taken from the sump 3 to the centrifugal pump through a conduit 24 and pump 21 discharges to a line 25 which, in turn, is connected, through a line 26 to the hydraulic cylinder at the end thereof opposite the end at which high pressure fluid is introduced. For bypassing the pump discharge, a line 27 is inter-connected between line 25 and the sump 3. The bypass line which may contain a throttling valve 28 provides for recirculation of the discharge from the centrifugal pump 21, whereby the hydraulic fluid is prevented from becoming overheated even though the machine is out of operation for a substantial period of time during which the centrifugal pump may be operating. A two-way pilot operated valve 28a may be included in the line 25 to provide control whereby the table may be "inched" gradually to a given position.

In the operation of the circuit which has just been described, it may be seen that both the centrifugal pump 21 and the positive displacement pump 1 may operate continuously, the centrifugal pump furnishing fluid to return the table at rapid traverse speeds following each cutting stroke and also furnishing fluid under low pressure to act as a load or steadyng tension on the table for preventing chattering during cutting strokes and to provide uniformity in the speed of table movement. Thus, with the cutting stroke being in the direction indicated by the arrow in Figure 4, fluid under high pressure introduced through the line 9 into the cylinder 10 will cause the table to move in a cutting direction and, at this time, low pressure fluid from the centrifugal pump will be expelled from the opposite end of the cylinder, returning to the sump 3 through the bypass line 27 or through the pump 21 in reverse flow, the actual course depending upon the setting of valve 28.

At the end of the cutting stroke the valve 8 is moved to the position which it occupies in Figure 4, whereupon the high pressure discharge from the pump is diverted through the line 19 to the sump. At this time fluid from the centrifugal pump 21 enters the cylinder to effect return traverse of the table, and the discharge of fluid from the opposite end of the cylinder proceeds through the line 9 through the annular recess 14 at the valve 8, and through the vent line 18 to meet the pump discharge of pump 1, which is now by-passing at the line 19 for return to the sump. By virtue of this arrangement there is no tendency for the discharge from the high pressure pump to block the flow of fluid being expelled from the ram.

The circuit just described is a simple system in which centrifugal and positive displacement pumps cooperate for traverse of the table through its cutting and return strokes.

A variable loading of the table during cutting may be obtained through a supplemental metering circuit which is indicated at 29 in Figure 4. This circuit comprises a conduit 30 interconnecting the line 25 with a metering valve 31, with a return line 32 extending therefrom to the sump 3. In the event this flow control circuit is used, a check valve 32a, may be installed in line 25 ahead of the inlet to the hydraulic cylinder,

whereby back flow from the cylinder through the pump or bypass line 28 is blocked. The flow control meter 31 serves the purpose of maintaining a back pressure in the hydraulic cylinder during the cutting stroke. It is to be observed that the valve 31 is set to pass hydraulic fluid at a pressure which is greater than that required to effect movement of the table in a return direction.

Thus, when high pressure fluid from the pump 1 is being introduced through the line 9 into the one end of the hydraulic cylinder to produce movement of the table in a cutting direction fluid expelled from the cylinder at the opposite end is blocked against flowing through the centrifugal pump 21 or relief circuits because of the check valve 32a and therefore proceeds through line 30, valve 31, and line 32 to return to the sump. However, the flow control unit 31 restricts the flow through this circuit to maintain a predetermined back pressure at the cylinder 10 to provide predetermined resistance to table movement. The flow control device 31 of the metering circuit may be of various types, one suitable unit commercially available being the Vickers Flow Control FX-2112B.

At the end of the cutting stroke hydraulic fluid passes directly from the centrifugal pump into the cylinder to effect rapid return movement of the table.

As shown in Figures 1, 2 and 3 these control units for both the high and the low pressure circuit are mounted conveniently upon the bed of the machine at points accessible to the operator, the pilot valves being located adjacent the table for dog actuation. Inasmuch as the valve and control units are conventional the structural details are not shown.

It is to be noted that multiple cutting speeds readily may be obtained by the employment of a constant delivery positive pressure pump and multi-speed motor for the high pressure circuit of the apparatus with a constant speed motor operating the centrifugal pump, and a variety of rapid traverse speeds being obtained through throttling of the centrifugal pump discharge. The high pressure pump, which necessarily is of more precise construction and therefore much more expensive to manufacture than the centrifugal pump, need have only the capacity to furnish fluid for the cutting speeds without the excess capacity which otherwise would be required merely for returning the table at low pressure.

The structure shown in Figure 5 comprises a high pressure positive acting pump and a low pressure high volume centrifugal pump for the purposes which previously have been described but these pumps respectively feed hydraulic rams which are oppositely arranged to drive the table through its cutting and return strokes. This modification provides the advantage of enabling the high pressure system to be located at one end of the table and the low pressure system at the opposite end thereby avoiding friction losses and the pressure drop attending the passage of fluid through pipe lines of substantial length.

The hydraulic rams are mounted in side by side relationship between the table and the bed, the ram 33 causing movement of the table in a cutting direction and the ram 34 in a reverse direction. In the preferred embodiment the cylinder of each ram is carried by the table and moves with it, the ends of the cylinders respectively being buttressed against suitable bosses 35 and 35a extending from the table. The pistons

are fixed to the bed and hydraulic fluid may be introduced in any suitable manner as for instance through openings in the piston rods. In the high pressure circuit the positive acting high pressure pump indicated generally at 36 is mounted upon a sump 37 which is located adjacent one end of the machine for instance between the side walls of the bed. This pump discharges through a line 38 to a dog actuated three-way valve 39 which is similar in construction to the valve 8 previously described in connection with Figure 4.

A conduit 40 extends from the valve 39 into connection with the "cutting" ram 33 and this line also may contain a throttle valve through which "inch" control of the table may be exercised. Intermediate the pump 36 and the valve 39 a relief circuit 41 is connected with the sump 37 and this circuit contains a suitable relief valve 42 while return lines 43 and 44 are also taken to the sump through the line 41 to accommodate back flow of hydraulic fluid from the cutting ram 33 during movement of the table in a return direction. Thus, upon actuation of the plunger in valve 39, the pump discharge line 38 communicates with the line 40 and high pressure fluid enters the ram 33 to actuate the table in a "cutting" direction. At this time the outlet ports 44 and 43 are isolated. Reverse actuation of the valve 39 breaks communication of the lines 38 and 40 and hydraulic fluid may then drain from the line 40 through the lines 44 and 41 to the sump 37.

In the low pressure circuit the centrifugal pump is indicated at 45. It is connected through a line 46 with a sump 47 and discharges to a line 48 which extends to the low pressure or "return" ram 34. A check valve 49 is located in the conduit 48 arranged to prevent return flow through the pump and a throttle valve 50 also is provided for "inch" control of the table under the actuation of the low pressure pump. Between the check valve 49 and the "inch" control valve 50 a return line 51 is taken to the conduit 46 extending from the sump and this circuit contains a metering valve 52 which has the same purpose as the valve 31 described in connection with Figure 4 and also contains a throttle valve 53 having a pilot thereon positioned to be actuated by dog means located on the planer table. Thus the check valve 49 causes hydraulic fluid to pass from the centrifugal pump 45 to the ram 34 to effect movement of the table in a return direction while hydraulic fluid expelled from the ram 34 during table movement in an opposite direction is diverted through the flow control device 52 whereby a steady force is exerted upon the table during cutting. The metering circuit also provides for recirculation of fluid to prevent overheating during periods in which the table is not being actuated.

Having described my invention, I claim:

1. A hydraulic actuating system, comprising a hydraulic cylinder and piston slidably therein, a centrifugal pump, a positive displacement pump, a reservoir, means including a valve for directing fluid from said positive displacement pump into the cylinder at one side of said piston to effect an actuating movement in one direction and then to divert the flow of fluid from said pump to said reservoir, means for directing discharge from said centrifugal pump into the cylinder at the opposite end of said cylinder continuously, a check valve in said continuous centrifugal pump discharge line before the inlet to said cylinder to

check the return flow to said centrifugal pump, and a metering circuit connected with said cylinder beyond said inlet point for metering the expulsion of oil therefrom under movement of said cylinder effected by introduction of fluid from said high pressure pump.

2. A hydraulic actuating system for effecting translation of the reciprocating element of a machine tool in which work is performed on a workpiece in one direction of travel of said element only, said system comprising: a hydraulic cylinder and piston slidable therein, a centrifugal pump, a positive displacement pump, a reservoir, means including a valve for directing fluid from said positive displacement pump into the cylinder at one side of said piston to effect an actuating movement thereof in one direction and then to divert the flow of fluid from said pump to said reservoir, an actuating member mounted upon the reciprocating element and cooperating with the valve to shift said valve to and from the said cylinder-flow directing positions respectively at the limits of travel of said reciprocating element, the face of the said piston which develops work-producing pressure having an effective area not greater than the opposite face thereof, and means for directing discharge from said centrifugal pump into the cylinder at the opposite end of said piston continuously.

3. A hydraulic actuating system for effecting translation of the reciprocating element of a machine tool in which work is performed on a workpiece in one direction of travel of said element only, said system comprising: a hydraulic cylinder and piston slidable therein, a centrifugal pump, a positive displacement pump, a reservoir, means including a valve for directing fluid from

5 said positive displacement pump into the cylinder at one side of said piston to effect an actuating movement thereof in one direction and then to divert the flow of fluid from said pump to said reservoir, an actuating member mounted upon the reciprocating element and cooperating with the valve to shift said valve to and from the said cylinder-flow directing positions respectively at the limits of travel of said reciprocating element, 10 a rod mounted on that side of said piston which develops work-producing pressure, said rod extending through an end of the cylinder and having its outer end connecting to said reciprocating element for translation therewith whereby 15 said rod is under tension during the work stroke, and means for directing discharge from said centrifugal pump into the cylinder at the opposite end of said piston continuously.
